Primary Examiner — Cynthia R Underwood(74) *Attorney, Agent, or Firm* — Kelly & Kelley, LLP**CLAIM**

The ornamental design for a hinge, as shown.

DESCRIPTION

FIG. 1 is a perspective view of a hinge embodying my new design;

FIG. 2 is a bottom view thereof;

FIG. 3 is a top plan view thereof;

FIG. 4 is a front view thereof;

FIG. 5 is a rear view thereof;

FIG. 6 is a right side view thereof; and,

FIG. 7 is a left side view thereof.

The dotted circular lines show typical areas where apertures are provided for mounting the hinge. The broken lines depict portions of the hinge that form no part of the claim.

1 Claim, 7 Drawing Sheets(56)
